US0D1029345S

(12) **United States Design Patent** (10) **Patent No.:** **US D1,029,345 S**
(45) **Date of Patent:** **** May 28, 2024**

(54) **LAMP**

(71) Applicant: **Shenzhen Valed Lighting CO., LTD,**
Shenzhen (CN)

(72) Inventor: **Yanxi Du**, Shenzhen (CN)

(73) Assignee: **Shenzhen Valed Lighting CO., LTD,**
Shenzhen (CN)

(**) Term: **15 Years**

(21) Appl. No.: **29/909,573**

(22) Filed: **Aug. 8, 2023**

(51) LOC (14) Cl. **26-05**

(52) U.S. Cl.

USPC **D26/104**

(57) **CLAIM**

The ornamental design for a lamp, as shown and described.

DESCRIPTION

FIG. 1 is a front, right and top perspective view of a lamp, showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.

The broken lines shown in the drawings illustrate portions of the lamp that form no part of the claimed design.

1 Claim, 7 Drawing Sheets
